E. J. LONN.
CYCLE PART.
APPLICATION FILED DEC. 10, 1913.

1,101,131.

Patented June 23, 1914.

UNITED STATES PATENT OFFICE.

EDWARD J. LONN, OF LAPORTE, INDIANA, ASSIGNOR TO GREAT WESTERN MFG. CO., OF LAPORTE, INDIANA, A CORPORATION OF ILLINOIS.

CYCLE PART.

1,101,131.

Specification of Letters Patent. Patented June 23, 1914.

Application filed December 10, 1913. Serial No. 805,715.

To all whom it may concern:

Be it known that I, EDWARD J. LONN, a citizen of the United States, residing at La porte, in the county of La porte and State of Indiana, have invented a new and useful Improvement in Cycle Parts, of which the following is a specification:

The term "fittings," as used in the art of bicycle-construction, signifies the unions of the frame-forming tubular bars with the "parts," meaning the crank-hanger barrel, the seat-post and the steering-heads. It is the common practice to make these fittings with nipples projecting from the bodies of the parts and having secured in them, to project beyond their outer ends, reinforcing sleeves forming with the extremities of the nipples square shoulders against which the ends of the tubes abut to produce flush joints. This construction renders the joint very weak, because its strength is only that of the two thicknesses of metal, namely the tube and the sleeve telescoping it.

The object of my improvement is to provide a construction of fitting whereby the joint shall contain three thicknesses of metal, namely, the nipple, the sleeve and the tube, and thus add greatly to its strength and consequently to that of the frame.

In the accompanying drawing, Figure 1 is a view in elevation showing a crank-hanger provided with my improvement; Fig. 2 is a similar view showing a seat-post crown provided with the same; Fig. 3 is a similar view showing a steering-head provided with my improvement, and Fig. 4 is a broken view showing my improved construction of union in section.

A crank-hanger barrel is shown at 5 in Fig. 1, a seat-post crown at 6, on a stem 7, in Fig. 2, and a steering-head at 8 in Fig. 3. The hollow bodies of these parts have nipples 9 projecting from them, as usual, and in each nipple is confined a reinforcing sleeve 10, flanged at its inner end against the inner wall of the body, as represented at 11 to rigidly secure it in place, the outer end of the sleeve, which projects beyond the nipple, being provided longitudinally with V-shaped recesses 12, to render these ends resiliently compressible for facilitating the telescopic application to them of the frame-tubes 13 of a bicycle.

My improvement consists in reducing or tapering the outer-end portion of the nipple 55 to form it with a species of neck 14, of a diameter that will adapt it to fit into the end of a tube 13 and present a sloping shoulder 15 to meet the extremity of the tube. In this way I avoid cutting off the end of the nipple 60 to form the square abutting shoulder referred to, and merely reduce the diameter of the nipple leaving all the metal and the full strength thereof to be lapped by the tube-end. The neck 14 fits or is clenched into a 65 depression formed at 16 about the reinforcing sleeve of a depth to cause the outer surface of the neck to extend flush with that of the sleeve beyond the outer end of the depression. This depression conforms in shape 70 to the inner surface of the neck 14, thereby locking the reinforcing sleeve to the nipple.

By applying a frame-tube 13 telescopically over a sleeve 10, it overlaps the neck 14 and abuts against the shoulder 15 to form with 75 the neck a flush joint composed of the three thicknesses of metal, namely the sleeve, the neck and the tube, thereby greatly augmenting the strength of the joint and adding materially to a cycle-frame (of which only 80 one tubular bar is shown at 13) formed with these joints.

As will be understood, the parts may be secured together at the joints in a usual manner, as by brazing.

What I claim as new and desire to secure by Letters Patent is:

A cycle-part comprising a hollow body having a nipple projecting from it and a reinforcing sleeve secured in the nipple to 90 extend beyond it and provided with a circumferential depression, the nipple having a reduced neck-section extending from a sloping shoulder and fitting and confined in said depression to interlock the sleeve 95 with the nipple, said neck being adapted to enter an end of a tube telescopically applied to it and said sleeve to abut against the sloping shoulder, for the purpose set forth.

EDWARD J. LONN.

In presence of—

WILLIAM RICE SMITH,
C. A. BAYLOR.
